UNITED STATES PATENT OFFICE

96,474

DESIGN FOR A CLOCK-CASE

Dudley S. Ingraham, Bristol, Conn., assignor to
The E. Ingraham Company, Bristol, Conn., a
corporation

Application June 15, 1935, Serial No. 57,283

Term of patent 7 years

To all whom it may concern:

Be it known that I, Dudley S. Ingraham, a citizen of the United States, residing at Bristol, in the county of Hartford and State of Connecticut, have invented a new, original, and ornamental Design for a Clock-Case, of which the following is a specification, reference being had to the accompanying drawings, forming part thereof.

Fig. 1 is a perspective view of a clock-case showing my new design;

Fig. 2 is a view thereof in front elevation; and

Fig. 3 is an edge view thereof.

The design is characterized by a body having a polygonal outline and a broad concentric band between the same and its dial-opening, the said band being traversed by regularly-spaced transverse straps.

I claim:

The ornamental design for a clock-case substantially as shown and described.

DUDLEY S. INGRAHAM.
